UNITED STATES PATENT OFFICE

165,648

SUBSTAGE CONDENSER FOR MICROSCOPES

Leigh B. Hall, Rochester, N. Y., assignor to Bausch & Lomb Optical Company, Rochester, N. Y., a corporation of New York

Application January 26, 1951, Serial No. 13,991

Term of patent 14 years

(Cl. D57—1)

To all whom it may concern:

Be it known that I, Leigh B. Hall, a citizen of the United States and a resident of Rochester, county of Monroe, and State of New York, have invented a new, original, and ornamental Design for a Substage Condenser for Microscopes, of which the following is a specification, reference being had to the accompanying drawing, forming a part hereof.

Fig. 1 shows a side view of a substage condenser for microscopes, embodying my new design.

Fig. 2 is a perspective view thereof.

The broken line showing of a part of a microscope in Fig. 1 is for illustrative purposes only.

I claim:

The ornamental design for a substage condenser for microscopes, substantially as shown and described.

LEIGH B. HALL.
